UNITED STATES PATENT OFFICE.

WILLARD BUCKLEN, JR., OF MARBLE ROCK, IOWA.

RESPIRATOR.

No. 913,688.

Specification of Letters Patent.

Patented March 2, 1909.

Application filed April 6, 1908. Serial No. 425,530.

To all whom it may concern:

Be it known that I, WILLARD BUCKLEN, Jr., a citizen of the United States, residing at Marble Rock, in the county of Floyd and 5 State of Iowa, have invented certain new and useful Improvements in Respirators, of which the following is a specification.

This invention comprehends certain new and useful improvements in respirators and 10 the object of the invention is to provide a simple, durable and efficient construction of device of this character which will enable a person surrounded by noxious gases, dust, or under water, to breath freely without inhal- 15 ing any of the deleterious matter, and the invention consists in certain constructions, arrangements and combinations of the parts that I shall hereinafter fully describe.

For a full understanding of the invention, 20 reference is to be had to the following description and accompanying drawings, in which:

Figure 1 is a perspective view of my im- 25 proved respirator; Fig. 2 is a longitudinal sectional view through the casing thereof; Fig. 3 is a transverse sectional view through the casing, and Fig. 4 is a detail view of one of the valves.

Corresponding and like parts are referred 30 to in the following description and indicated in all the views of the drawings by the same reference characters.

My improved respirator comprises a casing 1 of any desired construction and design, 35 formed with an inlet nipple 2 and outlet nipple 3, to which, respectively, hose (not shown) are attached.

The casing 1 is provided with a middle partition 4, dividing it into an inlet compartment A and an outlet compartment B. A valve 5 is arranged to seat against that end of the casing 1 which is formed with a nipple 2, such end constituting a valve seat for the valve, and the valve 5 is pressed normally 45 to its seat by means of a coil spring 6, as clearly illustrated in the drawing. The casing 1 is divided into two compartments A and B by means of a middle partition 4 and a valve 7 is adapted to seat itself against one 50 side of the partition 4, as a valve seat being pressed thereagainst by a coil spring 8, as shown. The partition 4 is formed with a preferably centrally located opening 9 de- 55 signed to establish communication between the compartments A and B, such communica- 100 tion being controlled by the valve 7. A

flared mouth piece 10 is formed on or secured to the casing 1, and the latter is arranged to be secured to the face of the operator by means of rings 11, or similar fastening devices se- 60 cured to the ends of the casing 1 and ar- ranged for the attachment thereto of adjust- 65 able straps 12, such straps being secured to rings 13 which are in turn secured to straps 14 constituting the head piece of the device. 65

From the foregoing description in connec- 70 tion with the accompanying drawing, it will be seen that when the device is strapped to the head of the operator, if it be a fireman, or diver, or the like, every inspiration 75 through the mouth piece 10 will draw in fresh air through the nipple 2, this inspiration being permitted by the valve 5, the spring 6 yielding for this purpose. Every exhalation of the person to which the device 80 is applied will be permitted to escape through the opening 9 of the valve 7, and through the compartment B of the casing 1.

It will thus be seen that I have provided a very simple, durable and efficient construc- 85 tion of respirator which will be useful for firemen, or divers, or other persons exposed to noxious vapors or fumes, or under water, the parts of the device being capable of being easily manufactured and readily assembled. 85

Having thus described the invention, what is claimed as new is:

A device of the character described, comprising a casing formed at its ends with inlet and outlet nipples and provided with a middle partition dividing it into two compartments, said partition being formed with an opening extending therethrough, the casing being further provided with a mouth piece and with an opening leading from the en- 90 trance compartment outwardly within the mouth piece, a valve yieldingly held against the inlet end of the casing and located within the inlet compartment whereby to control the admission of air through the inlet com- 95 partment and thence within the margin of the mouth piece, a corresponding valve located within the other compartment and a handle held against rotation to close the opening formed therein. 100

In testimony whereof I affix my signature in presence of two witnesses.

WILLARD BUCKLEN, JR. [L. s.]
